(57) **CLAIM**

The ornamental design for a flatware handle, as shown and described.

DESCRIPTION

FIG. 1 is a side elevational view of my invention on a knife; FIG. 2 is a top view of the flatware handle illustrated in FIG. 1, the bottom view being a mirror image thereof; FIG. 3 is the opposite side elevational view of my invention on a knife; FIG. 4 is a cross sectional view taken along lines 4—4 of FIG. 1; FIG. 5 is a second embodiment showing a top view of my invention on a fork; FIG. 6 is a side elevational view of the flatware handle illustrated in FIG. 5, the opposite side elevational view being a mirror image thereof; FIG. 7 is a bottom view of my invention on a fork; FIG. 8 is a cross sectional view taken along lines 8—8 of FIG. 5; FIG. 9 is a third embodiment showing a top view of my invention on a spoon; FIG. 10 is a side elevational view of the flatware handle illustrated in FIG. 9, the opposite side elevational view being a mirror image thereof; FIG. 11 is a bottom view of my invention on a spoon; and, FIG. 12 is a cross sectional view taken along lines 12—12 of FIG. 9. The front view of the knife, fork and spoon would not show my flatware handle design. The broken line showing of a portion of the knife, fork and spoon is for illustrative purposes only, and forms no part of the claimed design.
